UNITED STATES PATENT OFFICE.

NELS JAMES NELSON, OF CHICAGO, ILLINOIS, ASSIGNOR TO F. ENGELHARDT & SONS,
OF ST. JOHNSVILLE, NEW YORK, A FIRM.

DESIGN FOR A PIANO-CASE.

41,614.

Specification for Design.

Patented July 25, 1911.

Application filed March 17, 1911. Serial No. 615,122. Term of patent 7 years.

To all whom it may concern:

Be it known that I, NELS JAMES NELSON, a citizen of the United States, residing at Chicago, Illinois, have invented a new, original, and ornamental Design for Piano-Cases, of which the following is a specification, reference being had to the accompanying drawing, forming part thereof.

The figure is a perspective view of a piano case, showing my new design.

I claim:

The ornamental design for a piano case, as shown.

NELS JAMES NELSON.

Witnesses:

W. H. WILMOT,
C. M. OLSEN.
